UNITED STATES PATENT OFFICE.

ERNST HEDDAEUS AND RUDOLF NOTHNAGEL, OF BILBAO, SPAIN.

LIGHTNING-ARRESTER.

No. 895,752.

Specification of Letters Patent. Patented Aug. 11, 1908.

Application filed November 30, 1907. Serial No. 404,542.

To all whom it may concern:

Be it known that we, ERNST HEDDAEUS and RUDOLF NOTHNAGEL, subjects of the German Emperor, and residents of Bilbao, 5 Spain, have invented certain new and useful Improvements in Lightning - Arresters, of which the following is a specification.

Our invention relates to improvements in lightning arresters of that class in which a 10 spark gap is formed between two bodies the discharging surfaces of which are movable relatively to each other, so that the arc moves from one point of the gap to another one, whereby it will more readily be 15 destroyed.

The improvements are particularly designed for use in such devices that are used 20 for protecting electrical circuits and instruments from the destructive effect of lightning and other abnormally high tension currents. Devices of this class heretofore in use are not as effective as is required for a 25 reliable operation of electrical plants, but they give rise to violent disturbances and considerable variations of the tension of the 30 apparatus, whenever an atmospheric discharge occurs.

Now, the object of our improvements is to 35 provide an apparatus of this class, in which all the advantages of devices heretofore in use are combined. And for this purpose, the discharging surfaces are so constructed as to 40 increase their distance when moving relatively to each other, whereby the arc formed across the gap is safely destroyed.

Devices of this class heretofore in use and 45 particularly designed for protecting a circuit from lightning have been found unsatisfactory for protecting a circuit from abnor- 50 mally high tension currents, because, for this latter purpose, they were not sufficiently sensitive, and they could not be made more sensitive without considerably reducing the length of the sparking gap. On the other hand, devices designed for protecting the 55 circuit from high tension currents would not be reliable when used as lightning arresters, because the resistance of the grounding conductor is too high, which resistance, however, 60 could not be sufficiently reduced, because otherwise the dischargers were liable to be injured or destroyed by an arc of an excess- 65ive strength. Now, an important advantage

of our improved protecting device consists in the fact that it will be equally effective in 55 protecting the circuit from lightning and from high tension currents.

An important feature of the invention consists in having both discharging surfaces 60 movable, which movement takes place so as to raise the arc, whereby the latter is destroyed within a comparatively short time, and the high tension current is gradually conducted to the earth. This feature of our 65 invention is based on the fact, that the arc, by its thermal action, is caused to move upwards, which upward movement is assisted by the said mechanical means of raising the discharging part of the gap. We thereby succeed in gradually and safely destroying 70 the arc.

For the purpose of explaining the invention, we have shown an example embodying the same in the accompanying drawing, in which the same letters of reference have been 75 used in all the views to indicate corresponding parts.

In said drawing—Figure 1, is a vertical cross-section of the apparatus taken on the line A—A of Fig. 2, and Fig. 2, is a plan of 80 the same.

In the example shown in the drawing, the apparatus comprises a pair of wheels *a* and *b* mounted in suitable insulated bearings of a frame *c*. The wheel *a* connected to the high 85 tension conductor has a circular shape. The wheel *b* which is grounded is of a cam like outline, four cam surfaces being shown in the example illustrated. The radial extension of each of the cam surfaces gradually decreases from a certain maximum to a minimum. The wheels *a* and *b* are rotated by 90 suitable means, a spring actuated motor being suitable for small apparatus, while an electric motor will be used for larger sizes. 95 For this purpose, the wheels are connected to suitable pulleys *g* mounted on the same axes therewith. By the said motor the wheels are rotated in the direction of the arrows shown in Fig. 1. It will readily be 100 understood, that, by so rotating the wheels, the arc produced between the same will be raised upwards, whereby the thermal action of the same is assisted. It will therefore readily be destroyed. Furthermore, it will 105 be seen, that the spark gap which is com-

paratively narrow at the beginning will gradually become broader so as to increase to a maximum required for a satisfactory operation. The arc produced between the dischargers will therefore be safely broken by increasing the distance of the discharging surfaces, and it will be produced again either by the next cam surface of the same wheel, or by the next cam surface of another wheel 10 connected to the same conductor.

In the drawing, an apparatus is shown in which two wheels a, a and b, b are provided, the wheels a, a being both connected to the high tension conductor, while the wheels b, b 15 are grounded. The cam surfaces of the wheels b, b are displaced relatively to each other at angles of 45° . Therefore, when the arc traversing the gap between one of the pairs of wheels a and b is about to break on account of the increase of the distance of the discharging surfaces of the same, the discharging surfaces of the other pair of wheels have so far approached each other, that an 20 arc can be formed across the same. If in this case the smallest distance of the discharging surfaces be x millimeters, and the difference of the radii of the discharging cam surfaces y millimeters, the smallest spark gap will be $x+y/2$ millimeters.

30 Where three pairs of wheels are connected in shunt, the cam surfaces of which are displaced at angles of 30° , the spark gap can not be more than $x+y/3$ millimeters.

In case of multiphase currents we prefer to 35 rigidly connect the wheels of the different conductors.

By the arrangement described apparatus of any desired degree of sensitiveness can be made, in which, notwithstanding, the arc is 40 safely destroyed.

The speed of the discharging surfaces

varies between 0.25 and 0.75 meters per second.

We claim:

1. An apparatus of the character described, comprising two rotating discharge bodies connected respectively to the circuit to be protected and to the earth, one of said bodies having thereon a plurality of cam surfaces, whereby the distance between said bodies will be varied as they are rotated. 45

2. An apparatus of the character described, comprising two rotating discharge bodies connected respectively to the circuit to be protected and to the earth, and one of said bodies having a peripheral cam adapted 55 to gradually vary the distance between said bodies as it passes the other body.

3. An apparatus of the character described, comprising a pair of oppositely rotating discharge bodies mounted on parallel axes, one of said bodies having a peripheral cam whereby the space separating said bodies will be gradually varied in width as 60 said bodies rotate. 65

4. An apparatus of the character described, comprising a plurality of pairs of discharge wheels respectively connected to the circuit to be protected and to the earth, means to rotate one wheel of each of said pairs, and cam surfaces formed on said rotatable wheels, the positions of said cam surfaces relatively to the coöperating wheels 70 being displaced relatively to one another.

In testimony whereof we have signed our 75 names to this specification in the presence of two subscribing witnesses.

ERNST HEDDAEUS.
RUDOLF NOTHNAGEL.
